UNITED STATES PATENT OFFICE.

JOHN HAYS HAMMOND, JR., OF GLOUCESTER, MASSACHUSETTS.

SYSTEM OF SOUND-WAVE TRANSMISSION FOR CONSTANT-PITCH CONTROL.

Application filed June 3, 1918, Serial No. 237,972. Renewed August 5, 1921. Serial No. 490,112.

To all whom it may concern:

Be it known that I, JOHN HAYS HAMMOND, Jr., a citizen of the United States, and a resident of Gloucester, county of Essex, and State of Massachusetts, have invented a certain new and useful System of Sound-Wave Transmission for Constant-Pitch Control, of which the following is a specification.

Some of the objects of the present invention are to provide means to maintain a constant pitch of sound waves at a receiving station irrespective of the position of the sending station; to provide means to automatically vary the pitch of emitted submarine sound waves in accordance with the speed and direction of a movable sending station with reference to a receiving station whereby the pitch of the received submarine sound waves is maintained constant; to provide means to compensate for the speed and direction of a vessel carrying an oscillator so that the pitch received by a body controlled from said vessel will remain constant; and to provide other improvements as will hereinafter appear.

In the accompanying drawings, Fig. 1 is a diagram explanatory of the system of the present invention; Fig. 2 represents diagrammatically one form of apparatus for carrying out the present invention; Fig. 3 represents a plan of a sighting unit and a rheostat controlled thereby; and Fig. 4 represents a diagram of curves corresponding to a ratio of pitch to angle for different speeds.

Referring to the drawings and more particularly to Fig. 1, a torpedo 10 of the controlled type is indicated as under distant control from a boat 11 which is assumed to be traveling in the direction 12 at a speed of S knots. A sighting unit, such as a telescope 13, is mounted on the boat 11 and the line of sight 14 from the telescope 13 to the torpedo 10 forms an angle A with the direction 12 of the control boat 11.

For the purpose of controlling the torpedo 10 the boat 11 is provided with a submarine oscillator 15 from which sound waves are to be sent out to the torpedo 10 of a constant pitch regardless of the speed and direction of movement of the boat 11,

and in determining the formula for constant frequency it is assumed that the torpedo 10 is stationary. Assuming further that: 55
 V = Velocity of sound in water in feet per second.

S = Speed of boat in feet per second.

P = Pitch of sound emitted from boat 11 in cycles per second. 60

Q = Pitch of sound received by torpedo 10 in cycles per second.

T = Component of speed of boat 11 on the course 14 or $S \cos. A$ the increase in frequency (F) due to the motion of the boat 11;

$$F = \frac{TP}{V} = \frac{PS \cos. A}{V}$$

The frequency received by the torpedo 10, 70 assuming same to be stationary;

$$Q = P + \frac{PS \cos. A}{V}$$

For constant received frequency; 75

$$Q = \frac{PV + PS \cos. A}{V}$$

$$QV = P(V + S \cos. A)$$

$$P = \frac{QV}{V + S \cos. A}$$

From this formula the variation in the pitch of sound emitted from the boat 11 in cycles per second due to the variation and speed of the boat 11 is determined to have 85 the torpedo received frequency maintained constant.

By reference to Fig. 4 a graphic representation of the curve of pitch against angle A is shown in which the ordinates denote pitch emitted by the boat 11 and abscissas denote degrees for angle A . Thus for a given speed S of the boat 11 the plotted curve corresponds to E of Fig. 4 and for various speeds such for example as $\frac{3}{4} S$, $\frac{1}{2} S$, $\frac{5}{4} S$ and $\frac{1}{4} S$ curves similar respectively to F, G and H will be obtained. Since these curves correspond to the speed it is possible, knowing the constant speed of the boat 11, to vary the emitted pitch in accordance with 100 the curve for that speed to produce the constant pitch required to control the torpedo 10.

For actuating and controlling the move-

ments of the distant body 10 in response to transmitted sound wave signals, the body 10 is equipped with a sound receiving system and steering control such as shown for example in my co-pending application Ser. No. 136,249.

For the purpose of sending out sound waves of a predetermined pitch to produce the desired result the telescope 13 is mounted 10 to rotate with a spindle 16 which forms a substantially vertical axis mounted in suitable bearings 17 fixed to the boat 11. Concentrically arranged with respect to the spindle 16 there are a number of series of 15 resistance coils 20, 21, 22 and 23, four being shown by way of example, each of which corresponds to a certain speed of the boat 11. Thus series 20 corresponds to a speed $\frac{1}{4}$ S; series 21 corresponds to a speed $\frac{1}{2}$ S; 20 series 22 corresponds to a speed $\frac{3}{4}$ S; and series 23 corresponds to a speed S.

In order to obtain a definite relation between the movement of the telescope 13 through a given angle in sighting upon the 23 torpedo and the speed of the boat 11 the coils of the several series are connected respectively at one end by wires 24, 25, 26 and 27 to a conductor 30 forming one terminal of a resistance 31, and each coil of any series has a predetermined resistance value based upon an angular movement of the telescope 13. That this resistance value may be effective the free ends of the respective coils of the respective resistance series 35 are provided with contacts 32, 33, 34 and 35 which are located in the path of an adjustable contact 36 according to the position of that contact 36 upon a supporting arm 37 fixed to the spindle 16. The arm 40 37 is slotted to form a guide 40 for the contact 36 and the latter may be clamped in a desired position by a thumb nut 41 or like fastening means. The contact 36 is therefore arranged to slide radially across the 45 ends of the series of resistances and may be fixed at will opposite any series so that when turned in response to a movement of the telescope 13 it will successively engage the fixed contacts of the resistance coils with 50 which it is in alignment.

In Fig. 3 the contact 36 is fixed to operate in conjunction with a speed value represented by the resistance series 22 and thus any coil of this series which is engaged by the 55 contact 36 is brought into the circuit of the conductor 30, resistance 31, motor field 43 and conductor 44 from contact 36, which circuit is in shunt with the armature circuit including a battery 45, conductors 46 and 60 47 and a direct current motor 48. The speed of the motor 48 is thus determined by the coil of the series which is cut in and as the coil is proportional to the angular movement of the telescope 13, the motor

speed varies as the ordinate of the curve 65 corresponding to the angle A.

In order to produce a frequency corresponding to the required ordinate the motor 48 is connected to drive an alternator 50, of say 500 cycles per second, which operates the oscillator 15 in a well known manner to send out sound waves by means of the diaphragm 51 suitably mounted at a convenient submerged portion of the hull of the boat 11. The alternator 50 has a field 70 75 52 excited by the battery 45 of the circuit including the conductors 53 and 54 and resistance 55. The alternator 50 is connected by conductors 56 and 57 with the vibratory element 58 of the oscillator 15 which may be 80 of any well known type suitable for the purpose intended.

In describing the operation of the system it will be assumed that the torpedo 10 is stationary while the boat 11 from which the 85 sound waves are emitted is traveling at a speed of $\frac{3}{4}$ S knots in the direction of line 12. Since the series of resistances 22 corresponds to the speed $\frac{3}{4}$ S, the contact 36 is moved on the arm 37 to the position 90 shown in Fig. 2 and locked in such position by the thumb nut 41, so that as the telescope 13 is swung from one position to another the contact 36 will move correspondingly over the resistance coils of the series 22 and 95 thus vary the resistance of the motor field circuit. The respective coils of the series being proportioned with respect to the movement of the telescope through a given angle A in following the torpedo 10 it follows that the coils will control the field 43 and thereby the motor 48 so that its speed will vary an amount proportional to the ordinate of the curve corresponding to the angle A. In the case here under consideration 100 the curve of the pitch of emitted sound is represented by the line F of Fig. 4 and the contact 36 is set accordingly on the corresponding resistance series 22. The result therefore of varying the speed of the motor 105 in accordance with the pitch curve F is to vary in a similar manner the speed of the alternator 50 so as to produce a frequency 110 corresponding to the curve ordinate which will cause the oscillator 15 to give out a 115 corresponding frequency and one which will maintain the pitch of the received sound at the torpedo 10 constant.

While the foregoing has dealt with a torpedo as the controlled body it is to be understood that the invention is not to be so limited, as any type of controlled body may be employed in a similar manner, and while the sound waves are here referred to as submarine waves this does not mean that the invention is to be restricted to submerged oscillators or submerged receiving apparatus.

Having thus described my invention, I claim:

1. In an apparatus for transmitting sound waves, a movable sending station for emitting sound waves, a body at a distance controlled from said station by sound waves of a predetermined pitch, and means to vary the pitch of sound waves emitted by said station to maintain the predetermined pitch of the sound waves received by said body constant irrespective of the position of said sending station.

2. In an apparatus for transmitting sound waves, a movable station for emitting sound waves, a body at a distance controlled from said station by sound waves of a predetermined pitch, and means to vary the pitch of sound waves emitted by said station to maintain the predetermined pitch of the sound waves received by said body constant irrespective of the velocity of the movable station.

3. In an apparatus for transmitting sound waves, a movable station for emitting sound waves, a body at a distance controlled from said station by sound waves of a predetermined pitch, and means to vary the pitch of sound waves emitted by said station to maintain the predetermined pitch of the sound waves received by said body constant irrespective of the velocity and the angular deviation of said station with respect to said body.

4. In an apparatus for transmitting sound waves, a sending station for emitting sound waves mounted on a vessel, a body at a distance controlled by sound waves of a predetermined pitch, and means on said vessel to vary the pitch of sound waves emitted by said station to maintain the predetermined pitch of the sound waves received by said body constant irrespective of the course of said vessel.

5. In an apparatus for transmitting sound waves, a sending station for emitting sound waves mounted on a vessel, a body at a distance controlled by sound waves of a predetermined pitch, and a rotatable member on said vessel to vary the pitch of sound waves emitted by said station to maintain the predetermined pitch of the sound waves received by said body constant irrespective of the velocity of said vessel.

6. In an apparatus for transmitting sound waves, a sending station for emitting sound waves mounted on a vessel, a body at a distance controlled from said station by sound waves of a predetermined pitch, and means on said vessel for varying the pitch of sound waves emitted from said station in accordance with the angular deviation of said vessel with respect to said body whereby the pitch of the sound waves received by said body remains constant irrespective of the course of said vessel.

7. In an apparatus for transmitting sound waves, a sending station for emitting sound waves mounted on a vessel, a body at a distance controlled from said station by sound waves of a predetermined pitch, and means on said vessel for varying the pitch of sound waves emitted from said station in accordance with the angular deviation of said vessel with respect to said body and in accordance with the speed of said vessel whereby the pitch of the sound waves received by said body remains constant irrespective of the course and velocity of said vessel.

8. In an apparatus for transmitting sound waves, a sending station for emitting submarine sound waves mounted on a vessel, a body at a distance controlled from said station by submarine sound waves of a predetermined pitch, and means on said vessel for varying the pitch of said submarine sound waves emitted from said station in accordance with the angular deviation of said vessel with respect to said body whereby the pitch of the submarine sound waves received by said body remains constant irrespective of the course of said vessel.

9. In an apparatus for transmitting sound waves, a sending station for emitting submarine sound waves mounted on a vessel, a body at a distance controlled from said station by submarine sound waves of a predetermined pitch, and means on said vessel for varying the pitch of the submarine sound waves emitted by said station proportionately to the angular direction of said vessel with respect to said body and to the velocity of said vessel whereby the pitch of the received submarine sound waves remains constant irrespective of the course and velocity of said vessel.

10. In an apparatus for transmitting sound waves, a sending station for emitting submarine sound waves mounted on a vessel, a torpedo at a distance controlled from said station by submarine sound waves of a predetermined pitch, and means on said vessel for varying the pitch of said submarine sound waves emitted from said station in accordance with the angular deviation of said vessel with respect to the course of said torpedo whereby the pitch of the submarine sound waves received by said torpedo remains constant irrespective of the course of said vessel.

11. In an apparatus for transmitting sound waves, a sending station for emitting submarine sound waves mounted on a vessel, a torpedo at a distance controlled from said station by submarine sound waves of a predetermined pitch, and means on said vessel for varying the pitch of said submarine sound waves emitted from said station in accordance with the angular deviation of said vessel with respect to the course of said torpedo and with respect to the speed of

- 4
- said vessel whereby the pitch of the submarine sound waves received by said torpedo remains constant irrespective of the course and velocity of said vessel.
5. 12. In an apparatus for transmitting sound waves, a dirigible body, means located on a vessel at a distance for producing submarine sound waves of a predetermined pitch to control said body, a sighting unit on said vessel, and means controlled by angular movement of said unit for varying said sound wave producing means in proportion to the angular movement of said sighting unit whereby the pitch of transmitted sound waves is automatically varied to maintain a constant pitch of received sound waves at said dirigible body irrespective of the speed and course of said vessel.
10. 13. In an apparatus for transmitting sound waves, a dirigible body, means located on a vessel at a distance for producing submarine sound waves of a predetermined pitch to control said body, said means including a motor, a sighting unit on said vessel, and means controlled by angular movement of said unit for varying the speed of said motor in proportion to the angular movement of said sighting unit whereby the pitch of transmitted sound waves is automatically varied to maintain a constant pitch of received sound waves at said dirigible body irrespective of the speed and course of said vessel.
15. 14. In an apparatus for transmitting sound waves, a dirigible body, means located on a vessel at a distance for producing submarine sound waves of a predetermined pitch to control said body, an electrical resistance for governing the frequency of said sound waves, said resistance being variably arranged with respect to a given velocity of said vessel and to the angular deviation of said vessel from the course of said dirigible body, a sighting unit, and means operated by said unit for varying said resistance automatically in accordance with the angular position of said unit whereby the pitch of transmitted sound waves is varied to maintain a constant pitch of received sound waves at said dirigible body irrespective of the speed and course of said vessel.
20. 15. A system for transmitting compressional impulses including an aiming element movable with respect to other portions of the system, and means actuated by said movable aiming element to vary the frequency of the impulses transmitted.
25. 16. A system for transmitting submarine compressional impulses including an aiming element movable with respect to other portions of the system, and means actuated by said movable element to vary the frequency of impulses transmitted.
30. 17. A system for transmitting periodic impulses including an aiming element mov-
- able with respect to other portions of the system, and means actuated by movable aiming element to vary the frequency of the impulses transmitted proportional to the movement of said element. 70
18. A system for transmitting compressional impulses including a telescope movable with respect to other portions of the system, and means actuated by said movable telescope to vary the frequency of the impulses transmitted. 75
19. A system for transmitting submarine compressional impulses including a telescope movable with respect to other portions of the system, and means actuated by movement of said telescope to vary the frequency of impulses transmitted. 80
20. A system for transmitting periodic impulses including a telescope movable with respect to other portions of the system, and means actuated by movement of said telescope to vary the frequency of the impulses transmitted proportional to the movement of said element. 85
21. A system for transmitting compressional impulses from said system to a distant object, said system and said object being relatively movable and said system including an aiming element which may be kept directed upon said object during a relative movement between said system and said object, and including also means controlled by movement of said aiming element to vary the frequency of the impulses transmitted from said system as to cause said impulses 90 when received at said object to have a substantially constant frequency with respect to said object. 95
22. A system for transmitting compressional impulses from said system to a distant object, said system and said object being relatively movable and said system including a telescope which may be kept directed upon said object during a relative movement between said system and said object, and means controlled by said telescope and movable therewith to vary the frequency of the impulses transmitted from said system as to cause said impulses when received at said object to have a substantially constant frequency with respect to said object. 100
23. A system for transmitting impulses from said system to a distant object, said system and said object being relatively movable and said system including an aiming element which may be kept directed upon said object during a relative movement between said system and said object, and means controlled by said aiming element and adjustable thereby when so directed to 105 vary the frequency of the impulses transmitted from said system as to cause said impulses when received at said object to have a substantially constant frequency with respect to said point. 110
- 115
- 120
- 125
- 130

24. A system for transmitting impulses from said system to a distant object, said system and said object being relatively movable and said system including a telescope which may be kept directed upon said object during a relative movement between said system and said object, and means controlled by said telescope and movable in synchronism therewith to vary the frequency of the impulses transmitted from said system as to cause said impulses when received at said object to have a substantially constant frequency with respect to said object.
- 15 25. The process of transmitting impulses from a transmission system to a receiving system during a movement of one system with respect to the other involving a change of distance between said systems which consists in so varying the frequency of the transmitted impulses as to cause the impulses when received to have a substantially constant frequency with respect to the receiving system.
- 25 26. In a system for transmitting energy from a movable transmitter to a receiver spaced therefrom, adjustable means for subtending the angle of divergence of the course of movement of the transmitter with respect to the direction in which the receiver is located relative to the transmitter, and means for varying the character of the transmitted energy proportional to the angle of divergence subtended.
- 35 27. In a system for transmitting periodic vibrations from a movable transmitter to a receiver spaced therefrom, adjustable means for subtending the angle of divergence of the course of movement of the transmitter with respect to the direction in which the receiver is located relative to the transmitter, and means for varying the periodicity of the vibrations proportional to the angle of divergence subtended.
- 45 28. In a system for transmitting periodic vibrations from a movable transmitter to a receiver spaced therefrom, adjustable means for subtending the angle of divergence of the course of movement of the transmitter with respect to the direction in which the receiver is located relative to the transmitter, and means for varying the periodicity of the vibrations according to the angle of divergence subtended to a degree which renders constant the periodicity of vibrations received at the receiver.
- 5 29. In a system of communication, a transmitting station on one movable body, a receiving station on another movable body, said transmitting station including means for emitting waves of predetermined frequency, and means for varying the frequency of said waves proportional to the relative movements of said bodies.
- 10 30. In a system of communication, a pair of relatively movable bodies, a transmitting station on one of said bodies for emitting signal waves of predetermined frequency, means for varying the frequency of said waves according to the relative position of said bodies and means on the other of said bodies for receiving said waves.
- 15 31. In a system of communication, a pair of relatively movable bodies, means for emitting signal waves of variable frequency from one of said bodies, and a receiving device on the other of said bodies for receiving signal waves of one of said frequencies, said transmitting station including means for varying the frequency of the emitted waves proportional to the relative position of said bodies so that the frequency of waves received by said receiving device remains substantially constant during the relative movement of said bodies.
- 20 32. In testimony whereof I have hereunto set my hand this 27 day of May, 1918, at Gloucester, Mass.

JOHN HAYS HAMMOND, JR.
